UNITED STATES PATENT OFFICE.

CHARLES AUGUSTUS KENWORTHY, OF EAST ORANGE, NEW JERSEY, ASSIGNOR TO THE BECK DUPLICATOR COMPANY, A CORPORATION OF NEW YORK.

SPINDLE.

Application filed May 11, 1923. Serial No. 638,412.

To all whom it may concern:

Be it known that I, CHARLES AUGUSTUS KENWORTHY, a citizen of the United States, and a resident of East Orange, in the county 5 of Essex and State of New Jersey, have invented certain new and useful Improvements in Spindles, of which the following is a specification.

The invention relates to spindles or rollers, particularly such as are adapted to bear, rolled or stored thereon, material which it is desired to store in rolled form until needed for use and then to be unrolled from the spindle and if desired rerolled 15 thereupon.

One of the principal objects of the invention is to provide such a roller which may be easily and conveniently employed in connection with apparatus in which the material stored upon the roller is used, and which may be easily and quickly removed and replaced in a reversed position for re-winding the material thereon, as herein-after more particularly explained.

25 The invention consists in the novel construction, arrangement and combination of various devices, elements and parts, as set forth in the claims hereof, certain embodiments of the same being shown in the accompanying drawings and described in this specification.

In the said drawings,

Fig. 1 is a side view of a device embodying one form of my invention, showing also 35 a chuck engaging the same at one end (said chuck, however, being no part of my invention), the spindle, to save space in the drawing, being broken away near its central portion;

40 Fig. 2 is a longitudinal sectional view of the same;

Fig. 3 is a view similar to Fig. 1 but showing a modified form of the invention;

45 Fig. 4 is a longitudinal sectional view of the same;

Figs. 12, 13 and 14 are also detail views hereinafter more particularly described.

50 Fig. 8 is a view similar to Fig. 1 but showing a second modified form of the invention;

Fig. 9 is a longitudinal sectional view of the same;

Fig. 10 is a view similar to Fig. 8 but

showing a further modified form of the invention; and

Fig. 11 is a longitudinal section of the same.

In carrying my invention into effect in the embodiments thereof which I have selected for illustration in the accompanying drawings and description in this specification, and referring first more particularly to Figs. 1 and 2, I provide a cylindrical shaft or body 20, of wood or any suitable material. At each end of the same is a metal cap 21, shown in end view in Fig. 5. A pair of approximately semicircular perforations 22 are provided in the end of the cap 21, separated by a cross-bar 23, in which 70 is a perforation 24. In Figs. 1 and 2, a chuck 25 is shown at the left of the drawing, in engagement with one of the caps 21. It will be observed that this chuck 25, being of forked construction, is adapted to engage with the semi-circular perforations 22 in the end of the cap 21. It will of course 75 be understood that this chuck is adapted to be journaled in the frame of an apparatus in connection with which the spindle is being used, and that the outer end is adapted to engage with a crank or other suitable means (not shown in the drawings) for rotating the same.

I also provide a removable bearing-member 85 adapted to engage with the end of the spindle not engaged by the chuck. The form of bearing-member shown in Figs. 1 and 2, is shown in perspective in Fig. 6. The same comprises a bearing-pin 26 and a disk 90 27, one end of the pin 26 being adapted to be inserted in the perforation 24 in one of the caps 21 as shown in Figs. 1 and 2, and the other end to be inserted in a perforation or other suitable bearing in the apparatus 95 with which the spindle is being used. The disk 27 is adapted to prevent the pin 26 from extending too far into either of the said perforations, and thereby becoming disengaged at its other end.

100 The operation of this embodiment of my invention will be readily seen from what has been said with regard to the construction of the same. It will be understood that devices embodying the invention are intended for use in pairs, each of which will usually contain a portion of the material stored thereon, which material is to be

wound from one spindle to the other and if desired rewound from the second back to the first. The spindles are intended to be used in connection with machines or apparatus of appropriate character, which comprise on one side a chuck adapted to engage with one end of a spindle placed in said machine, and thereby rotate the said spindle, and on the other side a bearing adapted to receive the pin of the removable bearing-member and thereby support the other end of said spindle and permit the same to freely rotate. My improved spindle therefore is placed in such a machine, the cap 21 on one end being engaged by the chuck, and the pin of the removable bearing-member at the other end being inserted in the bearing in the said machine. The spindle is then in a position which permits it to be rotated by the chuck so as to wind up thereupon material which it is desired to store thereon, the other spindle, from which the material is being unwound, being free to rotate in a backward direction so as to permit the material to be unwound therefrom. When it is desired to rewind the material from the second spindle back on to the first spindle, both of the spindles may be removed from the machine, the removable bearing-members removed and placed on the opposite ends of the spindles, and the spindles reversed end for end, the second spindle then occupying the position formerly occupied by the first spindle, the removable bearing-members then engaging the caps on the ends of the spindles formerly engaged by the chuck, and the chuck engaging the caps formerly engaged by the bearing-member, each end being equally well adapted for each of these purposes.

In the form of the invention shown in Figs. 3 and 4, I provide a shaft or body 30, having caps 31, similar to the corresponding elements shown in Figs. 1 and 2. I also show a chuck 35 in engagement with one of said caps 31. The removable bearing-member, however, is of modified form, the same comprising a cap 36 (shown in end view in Fig. 7) adapted to be readily slipped over the cap 31, and provided with a bearing-pin 37 adapted to engage with a suitable bearing in the apparatus in connection with which the spindle is being used.

The operation of this form of my invention will be obvious from what has been said with regard to its construction and with regard to the operation of the first-described form of the invention.

In Figs. 8 and 9, I show a second modified form of removable bearing-member, used in connection with a shaft 40 having caps 41 which may be engaged by a chuck 45, all of said elements 40, 41 and 45 being similar to the corresponding elements in the forms previously described. This form of bear-

ing member is shown in side view in Fig. 13 and in end view in Fig. 14. The same comprises a forked portion 46 and a bearing-pin 47. The forked portion 46 is adapted to engage with a cap 41 in the same way as does the chuck, and the pin 47 is adapted to engage with a suitable bearing in the apparatus in connection with which the spindle is being used, in a manner similar to that already described in connection with other forms of the removable bearing-member. It will be observed that a central perforation in the cap 41 is unnecessary and may be omitted, if this form of bearing-member is used.

The operation of this form also will be obvious from what has been above said, and need not be particularly described.

In Figs. 10 and 11, I show, in connection with a shaft 50 and a chuck 55, a modified form of cap, shown in end view in Fig. 12. This cap 51 is substantially similar to the cap shown in Figs. 1 to 5 and 8 to 9, but has the sides of the portion beyond the end of the shaft cut away, so that the remaining portion of the cap comprises a band portion 52 encircling the end of the shaft 50, a cross-bar 53, having widened end-portions adapted to prevent lateral displacement of the chuck or of a forked bearing-member, when the same is in engagement with said cross-bar 53. The manner of engagement will be obvious from an inspection of the drawings and what has been above said. A removable bearing-member comprising a forked portion 56, and a pin 57, similar to that shown in Figs. 8, 9, 13 and 14, is shown in Figs. 10 and 11, although it is obvious that the form of removable bearing-member shown in Fig. 6 may be used with this form of cap, if the cap is provided with a central perforation in the cross-bar 53, similar to the perforation 24 shown in Fig. 5.

The operation of this modification of the invention will be obvious from what has been above said.

The advantages of my invention will also be obvious from what has been above said with regard to the construction and operation of the same.

I do not limit myself to the exact construction which I have shown and described, as it is obvious that various further modifications might be made in the same without departing from the spirit and scope of my invention.

Having thus described my invention, what I claim as new and desire to secure by Letters Patent is as follows:

1. In a spindle, the combination with a shaft provided at each end with a member having an opening adapted to be engaged by a chuck; of a removable member adapted to engage with one of said first named members not so engaged by a chuck and pro-

- vided with a pin adapted to engage with a bearing in the apparatus with which said spindle is adapted to be used.
2. In a spindle, the combination with a shaft provided at each end with an eccentrically located socket adapted to be engaged by a chuck and with a centrally located socket; of a removable member adapted to engage with one of said centrally located sockets and provided with a pin adapted to engage with a bearing in the apparatus with which said spindle is adapted to be used.
3. In a spindle, the combination with a shaft provided at each end with a bar extending across the end of said shaft and adapted to be engaged by a forked chuck; of a member having a forked portion adapted to engage one of said bars not so engaged by a chuck and provided with a pin adapted to engage with a bearing in the apparatus with which said spindle is adapted to be used.
4. In a spindle the combination with a shaft provided at each end with a member encircling the end of said shaft and having a bar, extending across the end of said shaft and adapted to be engaged by a forked
5. In a spindle, the combination with a shaft provided at each end with a member adapted to be engaged by a chuck; of a member comprising a cap adapted to receive a portion of one of said first named members not so engaged by a chuck, and provided with a pin adapted to engage with a bearing in the apparatus with which said spindle is adapted to be used.
6. In a spindle, the combination with a shaft provided at each end with a member adapted to be engaged by a chuck; of a member comprising a forked portion adapted to engage one of said first-named members not so engaged by a chuck and provided with a pin adapted to engage with a bearing in the apparatus with which said spindle is adapted to be used.

In witness whereof I have hereunto signed my name this 7th day of May 1923.

CHARLES AUGUSTUS KENWORTHY.
